JOSEPH HAUK, OF MILWAUKEE, WISCONSIN, ASSIGNOR TO HAUK MANUFACTURING COMPANY, OF MILWAUKEE, WISCONSIN, A CORPORATION OF WISCONSIN

CAN COVERING APPARATUS

Application filed April 23, 1930. Serial No. 446,687.

The invention relates to can-washing machines and more particularly to apparatus for replacing the cover on the can after the cover and can have been washed.

5 The main object of the invention is to provide a recovering mechanism which may be readily used or applied to can-washing machines of different forms or constructions and which is not dependent for its operation 10 upon the guiding of the covers to a position above the can to render the mechanism effective, but which permits the covers being delivered from the washing machine at any convenient point and provides for carrying 15 the covers from this point to a position over the can after the delivery of the can from the machine.

A further object of the invention is to provide a cover-handling apparatus in which 20 the covers delivered from the washing machine are picked up and carried by a movable electromagnet from said machine to the then stationary can and deposited thereon automatically.

25 A further object of the invention is to provide a cover-handling apparatus in which the covers are delivered one at a time upon a receiving support which is raised in proper timed relation with a swinging carrier to 30 bring the cover into magnetically attractive relation with an electromagnet on said carrier and is carried thereby to a position over the can, which has been previously discharged from the machine and is deposited 35 in proper position on the can.

The invention further consists in the several features hereinafter set forth and more particularly defined by claims at the conclusion hereof.

40 In the drawings Fig. 1 is an elevation view of one side of the discharge end of a can-washing machine equipped with a cover-handling apparatus embodying the invention;

45 Fig. 2 is a plan view of the cover-handling apparatus;

50 Fig. 3 is an elevation view of the other side of the discharge end of a can-washing machine equipped with cover-handling apparatus embodying the invention;

Fig. 4 is a vertical sectional view of apparatus embodying the invention, taken on the line 4-4 of Fig. 2, parts being broken away and parts being shown in section;

Fig. 5 is a detail sectional view taken on the line 5-5 of Fig. 2;

Fig. 6 is a detail sectional view taken on the line 6-6 of Fig. 5.

The washing machine herein shown does not of itself constitute the subject-matter of this invention so that it has not been shown in detail and only the discharge end of this machine has been shown, said machine herein particularly shown embodying the cover feed and can-turning mechanism of my co-pending application Serial No. 404,648, filed November 4, 1929, for can-turning machine, it being noted, however, that the present invention is designed for association with the delivery end of any suitable can-washing machine wherein the cans and covers are successively delivered from the machine.

Referring to the drawings, the can 8, which has been washed in the machine in an inverted position, is delivered by the turning mechanism, for example such as shown in the above mentioned application, in an upright position on the supporting platform provided by a series of rollers 9 mounted on a frame 10 from which said can is afterward moved by mechanism hereinafter described onto a gravity conveyor, not shown.

The covers 11, which are intermittently and progressively advanced through the washing machine in an upright position, by any suitable feed mechanism, for example such as shown in the above mentioned application, are delivered onto a chute or inclined guide 12 upon which they fall from a vertically disposed position and slide thereon, bottom side down, onto a movable, horizontal, receiving support 13, which is mounted on the upper end of a vertically reciprocating bar 14 slidably mounted and guided in the spaced arms of a bracket 15 secured to the machine below the chute 12.

The support 13 is intermittently raised and lowered by the mechanism more particularly shown in Fig. 3, wherein the numeral 16 designates a motor-driven shaft, 17 a cam mount-

ed on said shaft, 18 a bell crank lever pivotally mounted intermediate its ends at 19 on a bracket 20 secured to the side of the machine, and carrying a roller 21 that is held by the weight of the parts against the cam 17, said lever 18 being operatively connected by a link 22 with the intermediate portion of a lever 23. The lever 23 is mounted on a pivot 24 on the bracket 20 at one end and its outer free forked end 25 has its bifurcations operatively connected by spaced links 26 to a block 27 secured to the rod or bar 14.

With this construction, as the shaft 16 revolves continuously while the machine is in operation, the cam 17 acting through lever 18, link 22, lever 23 and links 26 causes the bar 14 and the cover support 13 to be intermittently raised and lowered, the timing being such that the support 13 is in lowered position to receive a cover as the cover is discharged from the washing machine.

On the side of the machine opposite to that carrying the support 13 spaced bearing brackets 28 are provided for a vertically disposed oscillatory shaft 29, which has a forked or yoke-shaped fitting 30 pinned to the upper end thereof and forked crank arm 31 secured to the lower end thereof, the fitting 30 pivoting on the top of the upper bracket 28. The forked crank arm 31 has a pivot block 32 pivotally mounted therein on pins 33 and has the forked end 34 of a link 35 pivotally connected at right angles to the pins 33 by a pivot pin 36. The other forked end 37 of the link 35 is similarly pivotally connected by pins 38 to a pivot block 39 which in turn is connected by a pivot pin 40 to the upper forked end 41 of a cam-operated lever 42 pivoted at 43 and carrying a roller 44 working in a grooved cam 45 mounted on the shaft. With this construction the shaft 29 is oscillated by the cam 45 through its action on the lever 42, link 35 and crank 31.

The yoke-shaped fitting 30 has a plate 46 secured to the arms thereof by screws 47 and this plate has depending spaced arms 48 mounted in slots 49 in the fitting 30 and co-operating with the cylindrical ends 49' thereof to form supporting bearings for a pivotal trunnion 50 which has a hollow, cylindrical portion 51 in which the tubular carrier bar 52 is adjustably secured by bolts 53, said bar being limited in its desired position of vertical inclination by an adjustable stop screw 54 mounted on the transverse portion of the fitting 30 and secured in the desired adjusted position by the lock-nuts 55.

Telescoping within the outer end of the carrier bar 52 is a smaller tubular bar 56 adjustably secured thereto by providing a series of spaced holes 57 to receive a pin 58 passed through one set of these holes and aligned holes in the bar 52. A forked arm 59 is secured to the outer end of the bar 56 and has a suitable iron-clad tractive electromagnet 60

suspended therefrom by its connection therewith by a pin 61.

The current supply wires 62 for the electromagnet may pass through the hollow bars 56 and 52 and one of these conductors may be connected to a direct current generator 63 while the other conductor is connected to the other side of the generator through a suitable circuit closure or switch mechanism 64, whose movable switch arm 65 is under the control of a plunger 66 held against a control cam 67 on the shaft 16 by a spring 68, the details of the switch mechanism itself not constituting part of this invention and hence only shown diagrammatically. The generator is suitably driven from the main power drive for the machine.

With the above construction the magnet 60 or cover-holding means is moved by the swinging of the carrier bars 52, 56 and the shaft 29 to a position over the cover support 13, by the action of cam 45, lever 42, link 35, crank 31, as the support 13 with the cover 11 thereon is raised from its lower, dotted line position, shown in Fig. 4 to its upper position, at which time the cam 67 has closed the circuit to the electromagnet to energize the same and the cover 11 is then attracted by said electromagnet and held thereby while the support 13 starts to move down under the action of the cam 17. As said support moves down the carrier arm formed by the parts 29, 52, 56 and 60, with the cover 11 suspended on the outer end thereof, swings from the position shown in full lines in Fig. 2 in the direction of the arrow to the position indicated by the dot and dash line 69, which brings the cover over and above the conical opening 70 of the then stationary can 8, which has been discharged from the washing machine and turned over by parts including a carrier member 71 of the aforementioned application. With the cover in this position the cam 67 allows the circuit control switch 64 to open the energizing circuit for the magnet 60 so that the cover is no longer held thereby and drops therefrom into the filling opening 70 of the can.

The can with the cover in place thereon is then moved off the short, horizontal platform formed by the rollers 9 by a pair of kickers or oscillatory arms 72, each of which is mounted on a vertically-disposed pivot shaft 73 journaled in bearing brackets 74 on the frame 10 and provided with a crank 75, said cranks being connected by a link 76 for simultaneously swinging both shafts 73 and arms 72 by means of a crank arm 77 secured to one of said shafts connected by a link 78 to the upper end of a weighted lever 79 pivoted at 80 and carrying a weight 81 at its other end which holds its roller 82 against a cam 83 on the rotating shaft 16. This cam 83 acting through the lever 79, link 78, cranks 77, shafts 73, link 76 and cranks 75 causes

the arms 72 to be intermittently swung in proper timed relation with the mechanism previously described to move the can forwardly after receiving its cover and thus start 5 it on its travel along a suitable gravity conveyor, not shown.

Thus by the proper timing of the movement of the cover-handling mechanism with that of the can-discharge mechanism, each can on 10 its discharge from the machine is automatically supplied with a cover which, if the operator at the feeding end of the machine is careful, will be the same cover that the can had when it came to the machine.

15 I desire it to be understood that this invention is not to be limited to any particular form or arrangement of parts except insofar as such limitations are included in the claims.

What I claim as my invention is:

20 1. In an apparatus of the character described, the combination with the can and cover-delivery station of a can-washing machine, of cover-handling means receiving the cover from the cover-delivery station including an oscillatory arm movable in a substantially horizontal plane, a cover-holding electromagnet mounted on said arm and adapted to suspend a cover therefrom and carry the same for deposit on the can at the can-delivery station of the machine, means for energizing said electromagnet, and control switch mechanism controlled by the machine for controlling said energizing means.

25 2. In an apparatus for the character described, the combination of a cover discharge guide, a movable cover-receiving and lifting support to receive a cover as it is discharged from said guide, a cover carrier including a movable electromagnet cooperating with said support to receive and carry said cover therefrom to a position for placing on a can, and means for controlling said electromagnet to cause it to carry the cover as above described and release it when positioned for placement 45 on the can.

30 3. In an apparatus of the character described, the combination of a cover discharge guide, a movable carrier including a cover-holding electromagnet, means for receiving a cover from said discharge guide and moving it to a position for said electromagnet to receive the same, means for moving said carrier from a cover-receiving position to a position over a can, means for energizing said electromagnet, and control means for said energizing means to cause said electromagnet to hold the cover during the movement of said carrier to a position over the can and to de-energize said electromagnet to 55 release the cover from the same when over the can to allow the cover to drop into place in the mouth of the can.

35 4. Apparatus for placing a cover upon a can discharged from a can-washing machine 60 wherein the covers are separately discharged

at one side of said machine, comprising a reciprocating, cover-receiving and lifting support to receive a cover as it is discharged from the machine, means for reciprocating said support, a carrier provided with an electromagnet cooperating with said support to receive the cover therefrom when said support is in elevated position, means for moving said carrier from cover-receiving position to a position over the can, and control 75 means for said electromagnet to release the cover from the same when over the can to permit the cover to drop into place in the mouth of the can.

5. Apparatus for placing a cover upon a can discharged from a can-washing machine wherein the covers are separately discharged at one side of the machine, comprising a cover discharge guide, a reciprocating, cover-receiving and lifting support to receive a cover as it is discharged from said guide, means for reciprocating said support, a carrier provided with cover-holding means cooperating with said support to receive a cover therefrom when said support is in elevated position, means for swinging said carrier from cover-receiving position to a position over the mouth of the can, and means to release said holding means to permit the cover to drop into place in the mouth of the can.

6. In apparatus of the character described, can-handling mechanism comprising a cover discharge guide, a reciprocating, cover-receiving and lifting support to receive a cover as it is discharged from said guide, means for reciprocating said support, a carrier provided with an electromagnet cooperating with said support to receive a cover therefrom when said support is in elevated position, a platform at the discharge end of the machine for receiving a can from the turning mechanism of said machine, means for swinging said carrier from cover-receiving position to a position over the mouth of the can, control means for said electromagnet to release the cover from the same when over a can to permit the cover to drop into place in the mouth of the can, and means for advancing the covered can along said platform.

7. The combination of a cover discharge guide, a reciprocating support to receive a cover as it is discharged from said guide, means for reciprocating said support, a carrier provided with an electromagnet cooperating with said support to receive the cover therefrom when said support is moved upwardly adjacent said electromagnet, means for moving said carrier from cover-receiving position to a position over a can, means for energizing said electromagnet, and control means for said energizing means to cause said magnet to hold the cover during the movement of said carrier to a position over the can and to de-energize said electromag- 120 125 130

net to release the cover from the same when over the can to allow the cover to drop into place in the mouth of the can.

8. In a cover replacing attachment for can washing machines, the combination with a cover discharge guide at one side of the machine, a reciprocating support to receive a cover as it is discharged from said guide, means for reciprocating said support, a horizontally swinging arm pivotally supported on the opposite side of the machine and having an electromagnet suspended from its outer end to receive the cover from said support when said support is moved upwardly adjacent said electromagnet, means for swinging said arm from cover-receiving position to a position over a can, means for energizing said electromagnet, and control means for said energizing means to cause said magnet to hold the cover during the movement of said carrier to a position over the can and to de-energize said electromagnet to release the cover from the same when over the can to allow the cover to drop into place in the mouth of the can.

9. In a device of the character described, the combination of a reciprocatory support having a horizontally disposed cover receiving portion, a cover discharge guide adapted to deliver a can cover on to said portion bottom side down, a horizontally movable arm provided with an electromagnet at the outer end thereof, means for reciprocating said support to bring the cover into operative relation with said electromagnet and then move away from said cover, means for moving said arm from a cover receiving position to a position over a can, means for energizing said electromagnet, and control means for said energizing to cause said magnet to hold the cover during the movement of said arm to a position over the can and to de-energize said electromagnet to release the cover from the same when over the can to allow the cover to drop into place in the mouth of the can.

In testimony whereof, I affix my signature.

JOSEPH HAUK.
